UNITED STATES PATENT OFFICE.

MAX FRED MANGELSDORFF, OF UNION HILL, NEW JERSEY.

HUMIDIFIER.

1,178,934.

Specification of Letters Patent. Patented Apr. 11, 1916.

Application filed April 29, 1914. Serial No. 835,107.

To all whom it may concern:

Be it known that I, MAX F. MANGELSDORFF, a citizen of the United States, and a resident of Union Hill, New Jersey, have 5 invented certain new and useful Improvements in Humidifiers, of which the following is a description in such full, clear, and exact terms as will enable any person skilled in the art to which it pertains to make and 10 use the same.

My invention relates to an apparatus for producing a humid atmosphere, generally known as a humidifier and it consists in its preferred embodiment in a casing containing 15 an evaporator surface above which is a fan or other means for drawing a current of air over the surface. Below the casing is a pan designed to contain water and a form of water elevator which raises a stream 20 of water and allows it to flow back over the evaporator surface against the before mentioned current of air. In this manner the water is vaporized and the vapor is absorbed by the air which passes off in a humid state 25 the degree of which depends upon the amount of vaporization.

The invention is not limited to the exact details and various features may be interchanged and substituted, but the accompanying drawings represent the preferred embodiment.

In these drawings Figure 1 is a vertical section of the apparatus. Fig. 2 is a sectional plan on the line 2—2 of Fig. 1 and 35 Fig. 3 is a sectional plan on the line 3—3 of Fig. 1.

As shown best in Fig. 1, the base of the machine has a pan 10, designed to receive water which may be supplied from any 40 source. I prefer, however, to employ one or more bottles 11, which are inverted on steps 12 and held thereby with their mouths at the designed water level, so that as soon as the water falls below this level additional 45 water is supplied from the bottles. When empty the bottles may be removed and filled ones again placed in position.

Supported on the pan by legs 14 is the 50 casing or body 15 which is preferably formed of sheet metal and contains a perforated bottom 16 on which is placed the

evaporator plates 17. These are set on edge and extend longitudinally of the casing for the whole or the greater part of the length thereof so as to provide a surface of wide 55 extent over which the water may flow in finely divided streams. Beyond the foregoing, the precise construction of the evaporator 17 is not material.

Above the evaporator is located the cap 60 or top 18 of the casing which communicates with the interior thereof by a throat 19 and which contains a fan 20. This may be of any form but is here shown as of the Sirrocco type. The motor (not shown) for 65 driving the fan may be located above the cap or top 19 of the casing.

21 indicates the outlet for the humid air.

The shaft 22 of the fan and motor is hollow below the fan and extends down to the 70 bottom of the pan 10 where its lower end is mounted in a step bearing 23 of any desired kind. At its bottom the shaft 22 has water inlet openings 24^a and above the evaporator the shaft has outlet openings 24. 25 75 indicates a screw or other form of water elevator which, according to the form here shown, is located in the bottom of the hollow shaft 22 and by the rotation of the shaft causes the water to flow upward from the 80 pan 10 to the outlet openings 24 from which it passes in streams over the evaporator and then flows down through the evaporator in films or finely divided streams.

The rotation or other operation of the 85 fan causes a current of air to be pulled upward from the bottom of the casing through the evaporator. This current of air meets the water flowing down the evaporator and the air takes up the water in the manner 90 described. The fan forces the air current out through the outlet 26 in the cap or top 18 from which the humid air is conducted to the place of its use.

I desire it understood that my invention 95 is not limited to the specific form of the various elements shown in the drawings but that these may be substituted by other forms of the instrumentalities shown. For example the fan and water elevator need not be 100 of the particular character shown; any other known type of fan and elevator may

be employed in their stead. The invention resides rather in the combination of elements than in their specific construction.

Having thus described my invention, what I claim as new and desire to secure by Letters Patent of the United States is:

In apparatus of the class described, an evaporating surface comprising a sheet and a corrugated spacing strip wound into a spiral whereby the successive turns of the

sheet are held spaced by the strip, and means for supplying moisture to the surface.

In testimony whereof I have hereunto signed my name in the presence of two witnesses.

MAX FRED MANGELSDORFF.
